SPECIMEN RECEPTACLE HOLDER

Edith E. Trichel and Dick C. Trichel,
Pineville, La.

Application January 27, 1950, Serial No. 140,878

2 Claims. (Cl. 4—110)

1

Our invention relates to a urine and feces specimen receptacle holder for toilets.

A primary object of our invention is to provide a holder for a urine and feces specimen receptacle, the holder being mounted upon the toilet stool or bowl beneath the toilet seat.

A further object is to provide a holder of the above mentioned character for use by hospitals, clinics, doctors' offices and the like.

A further object is to provide a urine and feces specimen attachment for toilets which is adjustable, highly simplified and compact in construction, strong and durable, sanitary and cheap to manufacture.

A still further object of the invention is to provide a device of the above mentioned character which will not interfere with the movement or positioning of the usual vertical swingable toilet seat.

Other objects and advantages of our invention will be apparent during the course of the following description.

In the accompanying drawings, forming a part of this application, and in which like numerals are employed to designate like parts throughout the same,

Figure 1 is a side elevation of a urine and feces specimen holder embodying our invention and showing the same applied to a conventional toilet stool or bowl.

Figure 2 is a plan view of the holder as shown in Figure 1, parts broken away,

Figure 3 is a fragmentary transverse vertical section taken on line 3—3 of Figure 1,

Figure 4 is an enlarged fragmentary transverse vertical section taken on line 4—4 of Figure 2, and

Figure 5 is a horizontal section taken on line 5—5 of Figure 4.

In the drawings, where for the purpose of illustration is shown a preferred embodiment of our invention, the numeral 10 designates a conventional toilet stool or bowl, including a flat horizontal top 11, provided with an integral inwardly projecting horizontal oval-shaped flange 12 extending entirely about the marginal edge of the top of the bowl 10 and forming the usual large oval-shaped top opening 13.

The stool 10 is equipped with a conventional vertically swingable oval-shaped toilet seat 14, having a flat bottom face 15 provided with a pair of forward depending rubber bumpers or feet 16 which contact the top 11 when the toilet seat is lowered to the horizontal position, Figure 1. The rear end of the toilet seat 14 is hingedly connected as at 17 in the usual manner to the usual

5 bracket 18, rigidly secured to the top 11 adjacent to the rear end of the stool 10. The seat 14 is maintained spaced slightly above the top 11 by the feet 16 and bracket 18, as shown, for forming a narrow horizontal passage or clearance space 19. This construction is all conventional and well known.

10 Our holder is removably mounted upon the top 11 of the bowl 10 beneath the seat 14, and comprises a pair of elongated transversely spaced thin strips or bars 20, preferably formed of steel, aluminum, or other suitable metal so that they will be substantially rigid. The strips or bars 20 are narrow and are disposed horizontally beneath the seat 14, the bars being substantially thinner than the height of the opening or passage 19. The bars 20 extend for substantially the entire length of the top of the bowl 10, and have their forward and rear ends resting upon the top 11 15 as shown. The bars 20 completely span the oval-shaped opening 13 and extend longitudinally of the top of the toilet bowl.

20 Adjustable means are provided for connecting the bars 20 and positively positioning them upon the toilet bowl 10 so that they will not be accidentally displaced longitudinally or laterally. Such means comprises forward and rear longitudinally curved or arcuate bands or plates 21 and 22, disposed directly beneath the bars 20 and extending transversely between the same. 25 The arcuate bands or plates 21 and 22 are provided at their opposite ends with vertically disposed flat extensions 22', integral therewith, and these extensions 22' engage beneath the bars 20 30 and extending transversely between the same. The arcuate bands or plates 21 and 22 are provided to the tops of the extensions 22' and preferably formed integral therewith are horizontally disposed flat rectangular tabs or plates 23, having openings 24 which register with forward and rear pairs of elongated longitudinally extending slots 25, formed in the bars 20 adjacent to the bands 21 and 22. The bands 21 and 22 are adjustably secured to the bars 20 by means of screws 26, including rectangular shank portions 27 which engage the sides of the slots 25, Figure 5, to prevent the screws from 35 turning. The screws 26 project below the tabs or plates 23 and have winged nuts 28 mounted thereon for clamping the tabs 23 tightly against the bottoms of the bars 20. The arcuate bands 21 and 22 extend transversely between the bars 20 and abut the forward and rear vertical edges of the oval-shaped opening 13. With the bands 21 and 22 thus contacting the edges of the oval-shaped opening 13, and the winged nuts 28 40 tightened, the bars 20 are secured together with

the bands as a unit which cannot move longitudinally or laterally with respect to the toilet bowl 10.

The arrangement thus provides a highly simplified unitary removable holder for a urine and feces specimen receptacle or cup 29, which may be generally cylindrical, and provided at its top with an annular radial flat horizontal flange 30, which engages upon the tops of the bars 20 for suspending the receptacle 29 between the bars. The flange 30 of the receptacle 29 is thin, and is preferably arranged slightly below the flat bottom surface 15 of the toilet seat. The arrangement is such that the receptacle 29 may slide longitudinally between the bars 20 so that it may be arranged in the desired position for receiving the urine or feces specimen. The receptacle may be provided with a handle 31 so that it may be conveniently lifted from between the bars 20 and removed when the specimen has been received.

It will be noted that the elongated slots 25 provide longitudinal adjustability for the bands 21 and 22 so that the receptacle holder may be adapted to different sizes and shapes of toilet stools having different sizes of top openings 13. It should be noted that the holder in no way interferes with the normal use or movement of the toilet seat 14, and there are no rough or sharp projections extending above the tops of the bars 20. Once the bands 21 and 22 have been properly adjusted for a given toilet stool 10, the holder may be applied to and be removed from the toilet stool as a unit.

While we have shown the screws 26 and associated elements for connecting the bars 20 and bands 21 and 22, we do not wish to limit ourselves to this precise means of connecting these elements, and the same may be connected by any other suitable means, such as by riveting, welding or the like. We also contemplate casting or molding the bars 20 and bands 21 and 22 as a unit from metal, plastics material, or the like.

It is to be understood that the form of our invention herewith shown and described is to be taken as a preferred example of the same, and that various changes in shape, size and arrangement of parts may be resorted to, without departing from the spirit of the invention or the scope of the subjoined claims.

Having thus described our invention, we claim:

1. A urine and feces specimen receptacle holder for a toilet stool including a substantially flat top

having an opening and a toilet seat mounted upon the substantially flat top and spaced a slight distance above the same, said holder comprising a pair of longitudinally extending elongated thin bars mounted upon the substantially flat top and spanning the opening, said bars being transversely spaced apart, forward and rear transversely extending arcuate bands disposed adjacent to the bottom of the bars and projecting below the bars and engaging the opposite ends of the opening, and mechanical means connecting said bands and bars together as a unit which may be applied to and removed from the toilet stool.

2. A urine or specimen attachment for toilet bowls having a top provided with an opening and a toilet seat mounted upon the top and spaced above the same, said attachment comprising a pair of elongated transversely spaced substantially parallel thin bars mounted upon the top beneath the bottom of the toilet seat and spanning the opening, the bars being provided near their forward and rear ends with transversely aligned pairs of elongated longitudinally extending slots, transversely extending arcuate bands arranged adjacent to the bottoms of the bars and projecting below the bars and into the opening, the bands engaging the forward and rear edges of the opening for positively positioning the bars upon the top of the toilet stool, the bands including horizontally disposed apertured tabs engaging the bottoms of the bars adjacent to the slots of the bars, screw means mounted within the slots of the bars and apertures of the tabs for adjustably securing the bands and bars together as a unit, and a urine specimen receptacle disposed between the bars and including a top horizontal annular flange engaging upon the tops of the bars for suspending the receptacle therefrom, the receptacle being longitudinally slidable between the bars.
